WELL PLUNGER

Application filed January 3, 1931, Serial No. 506,472. Renewed February 27, 1933.

My invention relates to well plungers and has as its principal object the provision of a well plunger wherein the various parts of the pump and rigging are connected together by screw threads and prevented from becoming loosened or detached.

The present application is a division in part of my copending application, Serial No. 429,189, filed February 17, 1930.

10 It is an object of the present invention to provide a well plunger having means for causing the liquid passing therethrough to exert a torque upon the threadedly connected parts of the pump and pump rigging so as 15 to keep the connections tight and prevent them from working loose while in operation.

Other objects will become apparent during the course of the following detailed description, when taken in conjunction with the accompanying drawing which forms a part of this specification, and in which;

20 Figure 1 is a longitudinal section of a portion of a well plunger, employing my invention;

Fig. 2 is a horizontal section taken on the line 2—2 of Fig. 1;

Fig. 3 is a longitudinal section of a portion of a well plunger illustrating a modified form of the invention;

Fig. 4 is a horizontal section taken on the line 4—4 of Fig. 3; and

Fig. 5 is a view in elevation of my pump and a portion of the rigging therefor.

35 Referring now to the drawing in detail and to Figs. 1 and 2 in particular, 5 indicates the working barrel in which the pump plunger 6 is reciprocated by means of a conventional rigging including a plurality of 40 threadedly connected rods 6a. The plunger 6 is made up of a plurality of threadedly connected sections, the upper one of which is threadedly connected with the lowermost pump rod.

45 The plunger 6 includes a vertically extending central oil pipe or conduit 7 which has its lower end threadedly engaged with the upper end of a cylinder 8 which may have the bore 9 thereof slightly enlarged below the connection with the pipe 7. Suit-

able wiping or polishing buffers 10 are provided around the pipe 7 and bear against the inner surface of the barrel 5.

A spiral blade 11 is mounted in the cylinder 8. This spiral blade 11 extends longitudinally of the cylinder and parallel with the side walls thereof. The outer edge of the spiral is in contact with the cylinder walls and may be secured thereto by welding 55 12 or in any other suitable manner. The 60 blade 11 is relatively narrow in width to present a relatively narrow lower spiral surface 13 with which the oil makes impact as it flows upwardly through the cylinder incident to a downward stroke of the 65 plunger. This arrangement permits the use of a comparatively long spiral without obstructing the flow of oil through the cylinder and yet the liquid striking the under surface 35 exerts sufficient torque as to maintain the various threaded connections of the pump plunger and rods in tight engagement. 70

The usual standing valve 14 is shown as being in engagement with the lifter 15 although it will be understood that the valve 75 14 will, during the operation of the pump, be seated at the bottom of the working barrel and out of engagement with the pump plunger. The valve lifter 15 may be threadedly engaged with the lower end of the 80 cylinder 8 and is provided with suitable oil passages 16 through which the oil passes into the cylinder and thence out through pipe 7 to the next section of the pump plunger. 85

Referring now to Figs. 3 and 4, which illustrate a modified form of the invention, the working barrel 5 has a pump plunger 17 working therein, the pump plunger 17 being operated as usual by a rigging including pump rods 6a. As in the case of the form of the invention shown in Figs. 1 and 2, the plunger includes a plurality of threadedly connected sections having a central vertical oil conduit extending therethrough and including the pipe 18 which has its lower end threadedly connected to the upper end of a cylinder 19, the upper end of the bore of the cylinder being reduced to receive the end of said pipe. 95 100

A baffle 20 of substantially spiral form is mounted within the bore of the cylinder 19. This spiral baffle is in the form of a twisted blade and is formed from a flat plate of steel or the like equal in width to the diameter of the bore of the cylinder 19. The baffle or blade 20 is secured within the cylinder by means of spot welds 21 or in any other suitable manner. The blade 20 is twisted in a direction so that oil passing upward through the cylinder 19 will strike the under face 22 of the spiral and exert sufficient torque to maintain the threaded connections of the pump and pump rods in tight engagement.

The puller 23 for the standing valve (not shown) is no part of the present invention, but forms the subject matter of another application.

It will thus be seen that I have provided an extremely simple device for maintaining the pump parts and rods in tight engagement and one in which there are no parts which can possibly get out of order. Also by changing the pitch of the spirals, the twisting force exerted on the plunger and rods may be readily regulated.

Although a preferred embodiment of the invention has been shown and described, it will be understood that various changes in the details of construction may be made without departing from the spirit of the invention as defined by the appended claims.

I claim:

1. In combination with a plurality of threadedly connected pump rods and a pump plunger operated thereby and having a longitudinal fluid conduit therethrough; means within said conduit for exerting a torque on said plunger and rods incident to the passage of fluid therethrough, said means comprising a baffle of substantially spiral form mounted within the conduit of said plunger said baffle having the opposite edges thereof secured to the walls of the conduit.

2. In combination with a plurality of threadedly connected pump rods and a pump plunger operated thereby and having a longitudinal fluid conduit therethrough; the conduit including a cylinder connected to the plunger means within said conduit for exerting a torque on said plunger and rods incident to the passage of fluid therethrough, said means comprising a baffle of substantially spiral form mounted in said cylinder whereby to maintain the threaded connections of said rods and pump in tight engagement, the width of the baffle throughout its length being substantially the same as the inner diameter of the cylinder.

3. In combination with a plurality of threadedly connected pump rods and a pump plunger operated thereby and having a longitudinal fluid conduit therethrough, a cylinder connected to the plunger in communication with the conduit and having a greater internal diameter than said conduit, a spiral blade secured to the wall of the cylinder and extending substantially the full length of said cylinder for exerting a torque on the plunger and rods incident to the passage of fluid thereto in order to maintain the threaded connections of said rods and pump in tight engagement.

JOHN W. PIPPIN.
